UNITED STATES PATENT OFFICE.

WILLIAM H. HONISSL, OF HARTFORD, CONNECTICUT, ASSIGNOR OF ONE-FOURTH TO HIMSELF, ONE-HALF TO BEECH-NUT PACKING COMPANY, OF CANAJOHARIE, NEW YORK, A CORPORATION OF NEW YORK, AND ONE-FOURTH TO WILLIAM A. LORENZ, OF HARTFORD, CONNECTICUT.

JAR-SEALING APPARATUS.

SPECIFICATION forming part of Letters Patent No. 789,693, dated May 9, 1905.

Application filed February 3, 1902. Serial No. 92,330.

To all whom it may concern:

Be it known that I, WILLIAM H. HONISSL, a citizen of the United States of America, and a resident of Hartford, in the county of Hartford and State of Connecticut, have invented 5 certain new and useful Improvements in Jar-Sealing Apparatus, of which the following is a specification.

This invention relates to improvements in 10 apparatus for exhausting and hermetically sealing jars, cans, and similar receptacles, and particularly relates to that class of apparatus in which the seal is made automatically by readmitting air-pressure after the desired 15 vacuum is obtained.

In the drawings, in which similar characters refer to similar parts, Figure 1 is a plan view of the jar receptacle and presser. Fig. 2 is a side view, in vertical section, of an exhausting-receiver containing a receptacle with jars therein and taken on the line 2 2 of Fig. 1. Fig. 3 is a fragmentary sectional view showing a modification of the apparatus.

The hermetic closures of vacuum-jars of 25 the type herein shown usually consist of a gasket and a cap C, having a flange which fits over the gasket and compresses it upon the jar to seal the closure after the exhausting operation, after which the seal is maintained by atmospheric pressure. In order to 30 obtain the best degree of vacuum within the jar, the caps should be maintained loosely upon the gaskets during the exhausting operation, and no weight should be brought to 35 bear upon the cover at that time.

The object of this invention is to provide a simple and conveniently-handled apparatus which can be placed within an exhausting-receiver for automatically making the seal by 40 the readmission of air-pressure after a suitable vacuum has been obtained in the apparatus and while excluding that pressure from the closure-joint.

In my improved apparatus I employ a 45 movable receptacle having a substantially inflexible presser which closes the open side of

the receptacle and is supported upon yielding supports, which partly or wholly sustain the weight of the presser during the exhausting operation, but which yields under the pressure of the readmitted air, thereby enabling the presser to close the caps upon the jars. The supports are adjustable and may be adjusted so as to hold the presser clear of the jars, as herein shown, or they may be adjusted 55 so that the presser rests with more or less weight upon the jars.

In the embodiment of my invention herein shown the presser 10 is employed in connection with a jar-receptacle 8, which may have 60 a stiffening-framework 9 around its open side to reinforce the receptacle against the sudden and severe pressure, due to the impact of the readmitted air-pressure. The receptacle 8, which may be of a size to suit one or more 65 jars J, is herein shown in a receiver R, having an air-exhausting pipe O and an inlet I. One or more of these receptacles 8 may be placed in a receiver, either stacked upon one another or side by side, according to the proportions 70 of the receptacles and of the receiver. The body or inflexible portion of the presser 10 substantially closes the open side of the receptacle 8 and is yieldingly supported upon pins 11 and springs 15, seated in the brackets 75 12. The pins are provided with nuts 14, which are kept from turning by means of the lower ends of the brackets or in any other suitable way. The pins are slotted or squared to receive a screw-driver or wrench, and by screwing the pins around the presser 10 may be adjusted nearer to or farther from the caps, as may be desired, or the pins may be lowered so that the presser 10 may rest upon the caps with a portion or all of its weight. I prefer, 85 however, to adjust the pins so that there will be sufficient space between the presser and the jar-covers to allow free displacement of the caps during the exhausting operation in order to permit the air to escape from the interior of the jars.

Various modifications of the presser-sus-

taining device may obviously be made by those skilled in the art.

The presser 10 may be made of any suitable material that will be substantially inflexible and that will press the covers down squarely upon the jars when the air has been readmitted to effect the sealing of the jars. The receptacle is provided with an outlet 17, through which the air in the jars and in the receptacle finds its exit during the exhausting operation. That opening is covered by a check - valve consisting of a flexible flap 16. During the exhausting operation this check-valve is lifted, and upon the readmission of air the valve prevents the return of the air to the receptacle through the outlet 17.

In Fig. 3 I have shown a modification of the presser 10, which is here provided with a flexible packing 18, making a close joint between the presser 10 and the side walls of the receptacle 8.

The operation of this apparatus is as follows: The receptacles 8 are filled with the desired number of jars, having their gaskets 25 and caps C in position. The presser 10 is then placed upon the pins 11, which sustain it in the desired relation to the jar-caps. The filled receptacle is then inserted in the receiver R, the door of which is then hermetically closed. The inlet I is closed, and air is exhausted through the pipe O from the receiver R and from the interior of the receptacle 8 and jars J through the opening 17, the air passing freely out between the caps and their gaskets, since little or no weight is placed upon the caps. When the desired vacuum has been obtained, air-pressure is readmitted through the inlet-valve I and operates to hold the valve 16 closed, preventing the readmission of air to the receptacle 8. The vacuum within the receptacle and within the jars being thus temporarily maintained, the readmitted air-pressure is exerted to its full extent upon the entire surface of the presser, 40 thus forcing it downwardly, and thereby forcing the caps C to their sealing positions upon the jars. The substantially inflexible character of the presser preserves it from being dished or buckled between the caps by the air-pressure, and the caps are thus leveled and forced squarely down upon the jars. After the caps are thus sealed the door of the receiver may now be opened and the jar-receptacle removed. Air is readmitted to the interior of the receptacle either before or after it is removed from the receiver by opening the flap-valve 16 in any convenient manner—as, for example, by the insertion of a thin-edged instrument between the valve and its seat in the wall of the receptacle. The admission of air into the interior of the receptacle counterbalances the atmospheric pressure on the upper side of the presser, which is then lifted clear of the jars by the action 55 of the springs 15 and may be removed, so as

to permit the removal of the jars and the insertion of a new lot of jars.

The valve device may be of any other well-known form—such, for example, as is shown in United States Patent No. 711,432, in which a supplemental lever is employed for the more convenient lifting of the valve. The receiver R may also be of any well-known form—such, for example, as is shown in my United States Patent No. 711,211. The door of the receiver is preferably hinged, so as to permit the ready opening and closing of the apparatus between the successive operations.

I claim as my invention—

1. In combination with an air-exhausting apparatus, a removable open-sided receptacle for a plurality of jars, a jar-presser substantially closing the open side of the receptacle, and yielding means for supporting the jar-presser in operative relation to the jars. 8c

2. In combination with an air-exhausting apparatus, a removable open-sided receptacle for a plurality of jars, a substantially inflexible jar-presser substantially closing the open side of the receptacle, yielding supports for 90 the jar-presser, and stops for limiting the upward movement of the supports.

3. In combination with an air-exhausting apparatus, a removable open-sided receptacle, a substantially inflexible jar-presser substantially closing the open side of the receptacle, yielding supports for holding the jar-presser, stops for limiting the upward movement of the supports, and means for adjusting the position of the yielding supports with relation 100 to the jars.

4. In a jar-sealing apparatus the combination of a removable open-sided receptacle for a plurality of jars, a substantially inflexible jar-presser, substantially closing the open side 105 of the receptacle, yielding means for supporting the jar-presser adjacent to and independently of the jars, means for exhausting air from both sides of the presser, and means for readmitting air-pressure first to the outer side 110 of the presser and then to the interior of the receptacle.

5. In a jar-sealing apparatus, the combination of an open-sided jar-receptacle, a substantially inflexible jar-presser, provided with a 115 packing for fitting the walls of the receptacle, and substantially closing the open side thereof, a return check-valve, yielding means for supporting the jar-presser adjacent to and independently of the jars, means for exhausting air from both sides of the presser, and means for readmitting air-pressure to the outer side 120 of the presser.

Signed at Hartford, Connecticut, this 1st day of February, 1902.

WM. H. HONISS.
